Specification for Design.

Patented June 2, 1914.

Application filed February 19, 1914. Serial No. 819,847. Term of patent 14 years.

To all whom it may concern:

Be it known that I, JOSEPH W. CHENEY, a citizen of the United States, residing at Three Rivers, in the county of Hampden and State of Massachusetts, have invented a new, original, and ornamental Design for a Protective Attachment for the Toe Portions of Shoes, of which the following is a specification, reference being had to the accompanying drawing, forming part thereof.

In the drawings:—Figure 1 is a perspective view of the protective attachment showing my new design. Fig. 2 is a plan view. Fig. 3 is a front view. Fig. 4 is a side view

showing the aspect of the attachment as applied on the toe portion of the shoe. Fig. 5 is a view, on an enlarged scale, showing the contour of the device as seen in section, taken on the line 5—5, Fig. 2.

I claim:

The ornamental design for a protective attachment for the toe portions of shoes, as shown.

JOSEPH W. CHENEY.
